UNITED STATES PATENT OFFICE

WILLIAM H. MEYER, OF ST. LOUIS, MISSOURI

MOTION PICTURE PROJECTOR

Application filed August 1, 1925. Serial No. 47,606.

This invention relates to improvements in motion picture projecting machines and more particularly to the non-theatrical type of projecting machines which are adapted for use in schools, churches, business establishments, etc. One of the desirable features of this type of projecting machine is to be able to set them up ready for use as quickly and with as few operations as possible. To accomplish this, the machines are usually equipped with incandescent lamps instead of the carbon arc lamps which are generally used in the theatrical type of projecting machine. The use of incandescent lamps eliminates considerable electrical apparatus and lightens and simplifies the structure. The candlepower of the incandescent lamps which are used in the non-theatrical type of projecting machine is much less than the arc lamps, however, they are practical where the throw of the picture, or in other words, where the distance from the projector to the screen, is within about fifty to seventy-five feet. Accordingly, if the throw is decreased, lamps of relatively less candlepower can be used.

In the non-theatrical type of projecting machine, it is quite often desirable to run the machine at various speeds below normal or to stop it entirely as when showing a "still" picture, and this is desirable in such cases where the machine is used for lecturing in the school room or where a salesman is demonstrating a machine or other product of a manufacturing establishment or for numerous other purposes.

It is well known that nitro-cellulose film, which is inflammable film, will ignite in a few seconds if the concentrated rays of light of an incandescent lamp of about 500 watt power or more are projected on the film when the latter is at rest or stationary, and this is due to the great amount of heat which is present in the light rays. It is also known that acetate-cellulose film, can safely withstand a slightly greater amount of the heat rays and that too much heat will blister and destroy it but not ignite it. The latter type of film is used to a great extent in non-theatrical projectors as a measure of safety.

Projectors which are used for purposes re-

quiring only a short throw of about ten to twenty feet, are equipped with a lamp having a candlepower which is low enough to permit the showing of "still" pictures without any danger of igniting or otherwise ruining either the standard inflammable or safety non-inflammable films.

Both of the above mentioned types of projectors are usually equipped with a revolving shutter to eliminate, what is usually called "travel ghost" in the picture. However when such shutters are used, it is a well known fact that the projected picture on the screen is only about one half as bright as the picture would be if no shutter is used. Also, projectors which are designed to show "still" pictures and equipped with incandescent lamps having a candlepower that will result in the burning or destruction of the film if the concentrated heat rays from the lamp are directly projected on the film when the latter is stopped, must be provided with a safety device to suppress or cut down the heat rays so that the amount of light projected on the film when the latter is stopped will be sufficient to show a "still" picture but will be insufficient to ignite or injure the film. Various means have been used to suppress the heat rays within safe limits, such as passing the light through water, glass, mice, or other translucent materials, and perforated metal plates.

Also, the above materials are usually applied to a shutter connected to a governor which is automatically positioned in the path of light rays between the lamp and film when the projector is stopped and positioned away from the path of light rays when the machine is operated and the film is in motion. As the revolving shutter which is positioned in front of the film, either between the film and the projecting lens or in front of the projecting lens reduces the amount of light on the screen when the shutter is revolving, and as the safety shutter which is positioned between the lamp and film suppresses the heat rays on the film, when the projector is stopped or a "still" is being shown, it can readily be seen that there is a tendency for the picture on the screen to be about the same

degree in brightness for a "still" picture as it is when the projector is running at normal speed, the amount of brightness in each case varying according to the size of the lamp and the kind of material used in the safety shutter.

In my Patent No. 1,413,050, issued April 18, 1922, I provide for a revolving shutter which is operable on the light rays when the projector is run at normal speed and which is automatically folded and inoperable on the light rays at speeds below normal or when the machine is stopped for showing a "still" picture. This shutter at no time obstructs the light rays when the projection is run below normal speed or when stopped. In the above patent I also provide for a safety shutter having a translucent material which suppresses the heat rays projected on the film a sufficient amount to prevent injury to the later. The safety shutter is operable by means of a governor and the revolving shutter is a governor in itself as it is controlled by a spring and by centrifugal force acting on each blade. Both of these shutters act independently and are adjusted separately and it requires considerable skill to adjust them so that they act at the same time to prevent, as much as possible, any noticeable difference between the brightness of the picture on the screen when the safety shutter becomes operable on the light rays and the revolving shutter becomes inoperable, or vice versa.

The main object of the present invention is to provide for direct cooperating means between the safety and revolving shutters whereby the safety shutter becomes operable on the light rays the instant the revolving shutter becomes inoperable or vice versa; and whereby the revolving shutter acts as its own governor and also as a governor for the safety shutter and provides for a single adjustment for this combination of shutters so as to eliminate the element of skill required where the shutters are adjusted separately.

Another object of the present invention is to provide an improved form of safety shutter which is cooperable with the light rays and with a foldable revolving shutter.

Another object is to provide a safety shutter having either a single or a plurality of perforated metal plates the perforations being so arranged that the center heat rays in the beam of light will be suppressed a greater percentage relative to the percentage that the outer heat rays are suppressed, and also that this percentage be gradually decreased a safe amount from the center rays to the outermost so that the maximum amount of light will be provided to show a "still" picture.

A further object is to provide a safety shutter having a heat ray suppressing safety means which is suitable for nitro-cellulose

film, and which can interchange with another heat ray suppressing safety means which is suitable for acetate-cellulose film; thus providing for the maximum amount of light within safe limits for a "still" picture for either type of film.

Other and further objects will appear in the specification and be specifically pointed out in the appended claims, reference being had to the accompanying drawings, exemplifying the invention, and in which:

Figure 1 is a plan view of the projector and lamp housing, being shown in section.

Figure 2 is a side elevation of Fig. 1 in which the lamp housing is shown in section.

Figure 3 is a transverse vertical section taken approximately on the line III—III of Fig. 1.

Figure 4 is an enlarged front elevation of the fire shutter.

Figure 5 is an enlarged vertical section taken on the line V—V of Fig. 4.

Figure 6 is an enlarged elevation of the fire shutter showing a modification of the form of perforated material used therein.

Referring by numerals to the accompanying drawings 1 designates a frame-work for the support of the mechanism of the machine and extended transversely and horizontally therethrough is a shaft 2, and secured to one end of said shaft is a turning crank 3, and secured to the opposite end of said shaft is a spur gear 4, and in mesh with said gear is a pinion 5 which is mounted on the shaft 6 of the film sprocket 7. In mesh with the spur gear 4 is a pinion 8, which is mounted on a horizontally disposed shaft 9, and secured on said shaft is a worm wheel 10, which is in mesh with a worm 11 which is secured to a longitudinally disposed shaft 12.

Slidably and loosely mounted on the shaft 12 is a grooved collar 13, and extended from said collar is a yoke 14, said yoke on one side being pivotally connected at 15 to an ear 16 which is extended at right angles from the blade 17 of a revolving or intermittent shutter 18, said blade 17 at its opposite end having a right angularly bent ear 19 extended therefrom, said ear 19 and ear 16 being swingably mounted on a pin 20, said pin being supported in a U-shaped member 21, which is rigidly secured to one side of a collar 22, said collar being rigidly secured to the shaft 12 by the pin 23.

Borne by the U-shaped member 21 in opposing disposition to the pin 20 is a pin 24, and mounted on one end of said pin is an ear 25 which is extended at right angles from the blade 26 of the shutter 18, said ear 25 corresponding to the ear 16 of the shutter 17 and extended at right angles from said blade 26 in opposite disposition from the ear 25 is an ear 27 which is mounted on the opposite end of the pin 24, said ear 27 corresponding to the ear 19 of the shutter 17. Mounted on

each of the pins 20 and 24 is a coil spring 28, one end of a respective spring being secured to a respective ear 16 and 25 through the hole 16a in the ear 16 and a corresponding hole 25a in the ear 25, whereas the opposite end of a respective spring bears against the U-shaped member 21.

Engaged within the groove of the collar 13 is a clutching portion 29 of a slidable bar 30, said bar being mounted on the bearing bracket 31 of the shaft 12 and is held in sliding position thereon by the screws 32 and depended from the intermediate portion of the bar 30 is an ear 33 bearing a pin 34, said pin being for engagement with the bifurcated end of the arm 35 of a rock lever 36, said lever being pivoted at 37 to the frame-work 1.

Borne by the frame-work 1 is a horizontally disposed projecting tube 38, and arranged rearwardly of said frame-work is a lamp housing 39 having its projecting tube 40 in alinement with the tube 38, and arranged in said tube 40 is a condensing lens 41 and disposed between said lens and the light emitting bulb 42 is a fire shutter 43, and depended from the frame 44 of said shutter is an arm 45 having its lower end rigidly secured to a shaft 46 which is supported in a bearing 47 which is extended from the lamp housing 39, and rigidly secured to said shaft on the outside of said housing is a lever 48 to which is secured a link 49, the depending end of said link being pivotally secured to the arm 50 of the rock lever 36.

The fire shutter 43 is provided with a pair of spaced apart apertured or perforated plates 51 which are secured in the frame 44, the apertures or perforations in the center of each of said plates being miniature in size, whereas the apertures arranged outwardly of the center of the plates are gradually increased in size. As the heat rays in a concentrated beam of light in the usual projecting machine are of the greatest intensity at the center of the beam and greatly increase in intensity from the center to the outermost rays, this manner of gradually increasing the size of the perforations in the plates 51 from the center to the outer edges of the plates, provides a means for suppressing all of the heat rays to a degree which gives as nearly as possible an even amount of heat rays through the entire transverse area of the light beam so as to provide the maximum amount of light that can be safely projected on the film when the latter is stationary.

In the operation of the mechanism, when the crank 3 is turned, power will be transmitted to the pinion 5 from the spur gear 4, and to the intermittent film driving sprocket 53 through the train of gearing thereto, and in which the picture film 52 will be caused to operate downwardly through the path of light projected from the tube 40 of the lamp housing 39, said spur gear 4 also causing the

shaft 9 to be revolved and the worm wheel 10 mounted on said shaft will become active on the worm 11 of the shaft 12, and inasmuch as the collar 22 to which the U-shaped member 21 is secured is rigidly fastened to said shaft 12, the revolving shutter 18 will be revolved thereby.

When the mechanism is being operated at about the required speed, the blades 17 and 26 of the shutter 18, which are normally held inwardly by the tension of the springs 28, will be forced outwardly by centrifugal action and inasmuch as the shaft 12 parallels the projecting tube 38 at a distance therefrom, each blade 17 and 26 will alternately pass through the light beam projected through said tube, the purpose of said blades being well known.

As the blades 17 and 26 of the revolving shutter 18 are thrown outwardly, the collar 13 and yoke 14 borne thereby, will be moved outwardly along the shaft 12 towards the shutter 18, and inasmuch as the bar 30 is in engagement with the groove of said collar by the clutching portion 29, said bar will also be moved outwardly as well as the arm 35 of the rock lever 36, and the arm 50 of said rock lever will be moved upwardly and the link 49 secured thereto will cause the lever 48 on the shaft 46 to move, and inasmuch as the fire shutter 43 is extended from said shaft, said shutter 43 will be thrown out of the path of the light rays projected through the tube 40 of the lamp housing 39 to the position shown in dotted lines in Fig. 3.

When the mechanism is slowed down or stopped, the springs 28 will become active on respective ears 16 and 25 of the blades 17 and 26 of the revolving shutter 18, thereby drawing said blades inwardly to their normal or neutral positions, and in which said ears 16 and 25 will be moved rearwardly and in consequence the collar 13 will also be moved rearwardly, and the bar 30 will cause the rock lever 36 to be returned to its normal position, thereby throwing the fire shutter back into its normal position into the projecting light rays thereby protecting the film from the heat units contained in the projecting light rays.

The type of plates 51 used in the fire shutter 43 and the size of perforations in said plates will be governed by the type or power of lamp used, and in instances where a lamp of small power is used, it may be desirable to use a single plate, but in instances where a high powered lamp is used, it is preferable to use two or more plates as shown in the drawings, or it may be desirable to use a single plate or a plurality of plates having a different number and size of perforations.

Attention is called to the co-operable relation of the revolving shutter 18 and the fire shutter 43, in which the revolving shutter is the governor for the fire shutter, said re-

volving shutter eliminating the heretofore separate and individual governor used in co-operation with a fire shutter.

The movement of blades 17 and 26 from closed position (as shown in Fig. 2) to open position as shown by the dotted line is substantially instantaneous as the blades revolve in a very small circle at the center when closed and in a much larger one when open.

- 10 It can readily be seen that there is a much greater amount of centrifugal force acting on the blades when in open position than in closed position and that this force increases rapidly as the blades are opening and that
- 15 the relative amount of increase is much greater than the increase in speed of rotation of shutter. Likewise, when the blades are closing, the action of springs 28 tend to quicken the closing movement as they will
- 20 tend to overcome the centrifugal force acting on the blades more rapidly as the blades are moved closer to the center of shaft. It can readily be seen that since the shutter 43 is cooperably connected to blades 17 and 26
- 25 and that there is a substantially instantaneous alternate change between the two shutters relative to their transverse positioning in the path of light and that therefore there will be no noticeable change in the light on the screen when the shutters are alternating their positions.

The disclosure in Fig. 6 is a modification of the fire shutter in which a body of wire mesh material such as a screen 54 is used, and in order to reduce the size of the meshes in the central portion of the material, a patch portion of material 55 is located against or adjacent the central portion of the material body 54. This arrangement of applying a patch portion to the mesh body will serve the same purpose as does the minute apertures formed in the plates of the shutter 43.

In the preferred form of my invention, the perforated shutter 43 is positioned between the lamp 42 and the lens 41, and it is to be understood that this shutter can also be positioned between the lens 41 and the film.

50 Various modifications in the arrangement and design of the above shutters may be made without departing from the spirit of my invention, and I contemplate the exclusive use of all such modifications which come within 55 the scope of my claims.

What I claim is:—

1. A motion picture projector provided with a fire shutter which is perforated over its entire area, the perforations in the center 60 of said fire shutter being smaller than the surrounding perforations.

2. A motion picture projector provided with a fire shutter which is perforated over its entire face, the perforations in the center of said shutter being small and graduating

in size as they extend outwardly from the center of said shutter.

3. In a motion picture projector, the combination of a movable fire shutter, a revolving shutter having a pivotal blade structure, a shaft to which said revolving shutter is rigidly secured, an element cooperable with the blade structure of said revolving shutter slidably mounted on said shaft, and means actuated by said element for moving said fire shutter into the projecting light ray of said projector.

4. In a motion picture projector, the combination of a movable fire shutter, and a revolving shutter having a pivotal blade structure, a shaft to which said revolving shutter is secured, a collar slidably mounted on said shaft adapted to be actuated by said revolving blade structure, a bar connected to said collar, and linkage connected to said bar and 85 said fire shutter.

5. A motion picture projecting machine having a movable fire shutter and a revolving shutter, said revolving shutter having a cutting-off element which is adapted to pass 90 through the light ray projected from the machine when said shutter is operating at substantially normal speed, said element adapted to be positioned out of the path of light when said revolving shutter is operating below said normal speed, and cooperable means connected to said fire shutter and said revolving shutter for operating said shutters in synchronizing relation.

6. A motion picture projecting machine 100 having a movable fire shutter and a revolving shutter, said revolving shutter having a plurality of cutting-off elements which are adapted to pass through the light ray projected from the machine when said shutter 105 is operating at substantially normal speed, said elements adapted to be positioned out of the path of light when said revolving shutter is operating below normal speed or when said shutter is stopped, and cooperable means 110 connected to said fire shutter and said revolving shutter for operating said shutters in synchronizing relation.

7. A motion picture projecting machine 115 having a movable fire shutter and a revolving shutter, said revolving shutter having a cutting-off element which is adapted to pass through the light ray projected from the machine when said revolving shutter is operating, said element adapted to be positioned 120 out of the path of light when said revolving shutter is stopped, and means cooperably connected to said revolving shutter and said fire shutter whereby said shutters will operate in synchronizing relation with respect to one another.

8. A motion picture projecting machine having a movable fire shutter and a revolving shutter, a shaft disposed parallel to the projecting ray of light of said machine for 125

the support of said revolving shutter, said revolving shutter having a cutting-off element which is adapted to pass through the light ray of said machine when said revolving shutter is operating, said element adapted to be positioned out of the path of light when said revolving shutter is inoperative on the light path, and connecting means cooperably disposed between said shutters for 10 operating said shutters in synchronizing relation.

9. The combination of a source of light and means for projecting a light beam therefrom, a plate positioned transversely in said beam, 15 said plate adapted to withstand the heat rays of said beam and having numerous perforations in substantially its entire area, the perforations in the center portion of said plate being smaller than the perforations in the 20 outer portion thereof.

10. The combination of a source of light, means for projecting a light beam therefrom, and a plate positioned transversely in said beam, said plate adapted to withstand the 25 heat rays in said beam and having numerous perforations therein which are smaller in size in the portion of the plate upon which said heat rays of greater intensity of said beam are directed.

11. The combination of a source of light and means for projecting a light beam therefrom, a plate disposed transversely of said beam having perforations forming passageways for transmitting part of the light rays 30 of said beam through said plate, the portion of said beam which is directed upon one side of said plate adjacent thereto having heat rays of greater intensity at one portion of its cross sectional area than at another, the disposition of and the sizes of the perforations of said plates comprising a means for suppressing the light rays in said beam so as to provide a substantially uniform amount of 35 heat over the entire cross sectional area of the portion of said beam directed from the other side of said plate and adjacent thereto.

12. A motion picture projector having a lamp and a film, means for directing a beam of light from said lamp to said film, a shutter 40 including a plate adapted to withstand the heat rays in said beam, said plate being positioned transversely of said beam and substantially covering the cross sectional area thereof and having perforations in substantially its entire area, the perforations in the center portion of said plate being smaller than the perforations in the outer portion thereof.

13. In a device of the class described, a 45 lamp, a film, means for directing a light beam from said lamp to said film, a shutter having a perforated plate positioned in said beam between said lamp and said film when the device is operating below a normal speed or stopped, said shutter adapted to be posi-

tioned away from the beam when the device is operated at a normal speed, the perforations in one portion of said plate being smaller than the perforations in another portion of said plate. 50

14. In a device of the class described, a lamp, a film, and means for directing a light beam from said lamp to said film, a shutter having a perforated plate positioned in said beam between said lamp and said film when 55 the device is operating below a normal speed, said plate adapted to be positioned away from said beam when the device is operated at a normal speed, said shutter providing means for suppressing a portion of the heat rays in said beam so as to give a substantially uniform distribution of heat rays over substantially the entire transverse area of said beam at and adjacent to said film. 60

15. A motion picture projecting machine 65 having a movable fire shutter and a revolving shutter, said revolving shutter having a cutting-off element which is adapted to pass through the light ray projected from the machine when said revolving shutter is operating, said element adapted to be positioned out of the path of light when said revolving shutter is operating either below a normal speed or when stopped, and means cooperably connected to said revolving shutter and 70 said fire shutter whereby said shutters will operate in synchronizing relation with respect to one another. 75

16. In a motion picture projector, the combination of a lamp, means for directing a 80 light beam from said lamp, a picture element positioned transversely of said light beam, a shutter having collapsable light cutting-off means adapted to pass into and out of the path of said light beam when the cutting-off means is in open position during the time when the shutter is operating at substantially normal speed, said cutting-off means adapted to remain out of the path of the light beam 85 when in a closed position when said shutter is operating below a normal speed or when stopped, partial heat suppressing means 90 adapted to be positioned transversely of the light beam between said lamp and said picture element when said shutter is operating below a normal speed or when stopped and adapted to be positioned out of the light beam when said shutter is operating at substantially normal speed, and means governed by 95 said cutting-off means connected to said shutter and said heat suppressing means for operating said heat suppressing means in synchronizing relation with said cutting-off means. 100

17. In a motion picture projector, the combination of a lamp, means for directing a light beam from said lamp, a picture element positioned transversely of said light beam, a shutter having light cutting-off means 105 adapted to pass into and out of the path of 110

said light beam when said shutter is operating at substantially normal speed, said cutting-off means adapted to remain out of the path of said light beam when said shutter is operating below a normal speed or when stopped, partial heat suppressing means adapted to be positioned transversely of said light beam between said lamp and said picture element when said shutter is operating below a normal speed or when stopped and adapted to be positioned out of the path of the light beam when said shutter is operating at substantially normal speed, and means governed by said cutting-off means and connected to said shutter and said heat suppressing means for operating said heat suppressing means in synchronizing relation with said cutting-off means.

18. The combination of a source of light directed upon an object and a perforated plate positioned between the source of light and the object transversely of the light beam from said light source, the arrangement of the perforations and contours and sizes of said perforations of said plate comprising a means for suppressing the heat rays in the light beam so as to provide a substantially uniform amount of heat over the entire cross sectional area of the light beam at and adjacent to said object.
